inventor:

Eduard Podszus

UNITED STATES PATENT OFFICE.

EMIL PODSZUS, OF BERLIN-FRIEDRICHSHAGEN, GERMANY.

PROCESS OF OBTAINING POWDERS OF GREAT FINENESS.

Application filed July 1, 1922. Serial No. 572,340.

To all whom it may concern:

Be it known that I, EMIL PODSZUS, a citizen of Germany, residing at Berlin-Friedrichshagen, Germany, have invented **5** certain new and useful Improvements in Processes of Obtaining Powders of Great Fineness, of which the following is a specification.

This invention has reference to a method **10** and means for effecting the comminution and disintegration of material and substances of any kind, particularly of metals, with a view to obtaining powders of extreme fineness which may be increased to colloidal **15** dispersion. Attempts have already been made heretofore of producing powders of the kind referred to without it having been possible however, to obtain such products in an easy and economical manner. Thus for **20** example, it has been suggested to produce metal powder by spraying and atomizing methods, but these suggestions presented great difficulties on account of the high **25** melting points of several metals, and it was scarcely possible to obtain the desired degree of purity and fineness, and besides all these methods caused very considerable expense. Similar conditions prevail in regard to the electrolytic methods.

30 Among the purely mechanical methods for the disintegration of metals and the production of powdered metals it is only the disintegrating process usually employed in the manufacture of bronze or brass which has **35** become of some importance for practical purposes. However, with that process the disintegration and comminution can only be carried out within comparatively narrow limits. Moreover, the process is rather com- **40** plicated and calls for comparatively super- **45** ior grades of material of very good tenacity. In the case of comparatively tough, and brittle material of great strength there great difficulties are encountered in the ex- **50** ecution of the process in which the metals are first rolled out into thin sheets which are then submitted to a kind of forging and stretching stage by means of which their thickness is further reduced whereupon they **55**

are pounded in mortars. Suggestions to **60** grind metals by means of the usual mills a large variety of which is in use for the comminution of other metals fail to produce satisfactory results. Even if it should be

possible to obtain a certain degree of disin- **55** tegration with devices of the kind referred to, it requires a very long time to grind even small quantities, and the operation is accom- **60** panied with such a very considerable wear of the parts of the mill, as to interfere with the economical working of the process. In the case of the majority of metals, how- **65** ever, the said method is not applicable at all. The difficulties presented in the methods of disintegrating the metals to **70** powder are due to the peculiar properties of the metals which, moreover, are the cause of their importance in the arts, particularly their tenacity, strength, and the property of small metal particles to become easily welded **75** to each other at higher pressures or higher temperatures, and while the strength and the tenacity of the metals require a greater amount of energy, the property last men- **80** tioned interferes with the application of considerable forces upon a plurality of metal particles.

In the case of mills the action of which is based upon the forcible tearing of the material to be ground between solid bodies, or in which the said material is projected against stationary bodies, an efficient disintegration, if at all possible, is coupled with great impurities particularly in the case of the comminution of metals. Furthermore, **85** the maximum capacity is soon reached be- **90** yond which no further disintegration can be effected. At any event, however, the disintegration and comminution requires so much time that economical working becomes im- **95** possible.

Colloid powders could be produced heretofore only by the usual colloidal methods allowing of the obtaining of small quantities only. Though recently colloidal masses have **100** become the subject of manufacturing meth- **105** ods the extremely large wear of the manu- **110** facturing instrumentalities allows only im- **115** pure products to be obtained, and in the case of hard and tough masses these methods fail to produce good results, and the entire procedure is not economical and cannot be used at all in the case of metals.

The knowledge of the causes involving **120** the difficulties in the manufacture of very fine powders has led to the present invention by means of which it is possible to obtain powders of any degree of fineness and purity

from any kind of metal, without danger of agglomeration or welding together. The process and the device according to my invention, besides comprising a great number of other advantages, are distinguished by the fact that the raw material does not need to consist of a high grade metal of superior quality, but the invention admits of the use of waste material, scrap and the like.

In accordance with my invention, the lumps or pieces of material to be comminuted are caused to act mechanically upon each other by being submitted to a very rapid continuous circular movement in the course of which they are caused to strike against each other with great force. This impact is continuously repeated, and it is possible in this manner, by imparting the necessary velocity to the rapidly gyrating whirling material to produce an extraordinarily fine distribution of the masses. With this end in view the several particles are distributed in a current of gas, air or other fluids or liquids, and two or more such currents charged with particles of the masses to be treated, are then caused to impinge upon each other. As has already been mentioned, it is of importance that the several particles are caused to perform a circulating movement, that is to say, that after the impact they are immediately carried along by the current, and are again made to impinge against each other. With a view to intensifying the results it is preferable to not only cause the several particles to impinge in a substantially rectilinear path, but to also impart to them a lateral movement, so that the intense whirling motion is also accompanied with as turbulent an interior motion as possible, so as to produce also a friction of the particles during the impact. By proceeding in this manner it is possible to comminute even the toughest kinds of metals with superior degrees of purity down to a fineness of the powder which it has been impossible to obtain heretofore.

For the practice of my invention the production of the necessary high velocity of the whirls is of importance, and consequently the particles are conducted in such a manner that they are prevented from directly impinging upon the relatively stationary parts of the mill employed, but are caused to move or slide along the same. The whirling velocity, that is to say the velocity of the currents in the direction of movement of the masses upon each other is preferably arranged so as to amount to about ten meters per second or more in the direction of the masses towards each other. But it is recommendable to increase the speed considerably beyond this ratio. In order to produce as extensive an action of the whirling masses as possible upon each other

they are conducted in such a manner that they are prevented from moving past each other, so that they are compelled to substantially fill up the entire casing of the mill.

If the process as heretofore outlined is carried out for many hours with the same amount of material a very fine powder is obtained thereby in which a colloid is already present. The separation of the colloid from the coarser particles is, however, difficult, and the proportion of colloid obtained is comparatively small.

However, in the further evolution of the process it is carried out with such perfection that pure colloids may be obtained in large quantities and in a comparatively short time. This is due to the fact that with the process outlined a certain state of equilibrium is obtained after some time in which even after prolonged grinding any appreciable comminution cannot be obtained. This state of equilibrium terminates in the case of coarser particles in the ratio of lightness of weight of the material in view of the fact that the mass of individual particles impinging upon each other, is gradually reduced to such an extent that any appreciable progress in the disintegrating operation becomes impossible.

In accordance with another improvement to which my invention refers, fine particles are, therefore, submitted to the comminuting operation accompanied by considerably coarser particles. The coarser particles possess the necessary mass in order to produce in this case the necessary forcible impact. With a proper selection of the proportions of the ingredients of fine and coarse particles there are so many fine particles contained between two impinging coarse particles that the fine particles are pounded, rubbed up or ground between them, while the coarser particles are submitted to only a rather slight or no appreciable wear at all. It is possible by acting in this manner, to convert the fine material in a very short time into large quantities of colloid.

The process becomes particularly efficient by simultaneously treating only fine and coarse particles, the medium sized granules being eliminated as much as possible, inasmuch as these particles possess only in a very imperfect degree the qualities referred to of the coarse particles, and because, on the other hand, these medium sized granules interfere with the systematic comminution of the small particles, and produce a rapid wear of the coarse particles. In the practical execution of the process the fine particles of the material to be comminuted are treated according to the process in certain proportions together with small balls of steel or the like. With a proper adjustment of the proportions of the fine

particles and of the steel balls the latter do not impinge directly upon each other, there being always a sufficiency of fine particles between them when the impact is to take place, and therefore no appreciable or noticeable wear of the steel balls takes place, but only the fine particles are rubbed up. By this operation quantities of metals may be converted into colloids up to 70 or 10 80 per cent in from four to five hours. The process may, for instance, be applied to particles of mass of a size of one hundredth of a millimeter or less, while the coarser particles, in the present instance the 15 steel balls, possess a diameter of, say one millimeter.

Where the greatest degree of purity of the mass is of importance it is advisable to use coarser granules of the mass to be 20 disintegrated itself as a treating medium for the finest powder, instead of using steel balls or other foreign bodies. According to the experiments made, it has been found to be of advantage to employ a large amount 25 of coarse particles or of steel balls or the like. However, the proportion of these coarser ingredients, provided they should not be greatly attacked, should not exceed one half the amount of the fine powder.

30 The process may also be carried out in such a manner that instead of adding coarser particles the fine powder is mixed with binding agents in suitable proportions, the said binding agents causing the formation 35 of lumps of some size, and the said lumps being then caused to act upon each other as coarse ingredients, and effecting the destruction and crushing of the fine particles of powder. In order to produce masses of 40 very extreme degrees of fineness, for example of colloidal fineness without the admixture of coarser particles, the invention provides for the insertion during the process of an additional current, thus for example an air current which is preferably 45 transversely directed with relation to the impinging currents, and which, without interfering therewith, is sufficient to carry off the finest particles away from the circulation. Into this separate current an additional 50 quantity of air is suddenly introduced which strongly dilutes the additional current referred to and thereby distributes the quantities of powder contained in that 55 additional current to a considerably larger volume of air. It then becomes possible to eliminate the several particles separately from each other from this strongly diluted air current by means of any suitable well 60 known or other methods, so as to finally arrive at the production of large quantities of absolutely fine particles without the admixture of coarser particles.

65 In spite of the great difficulty presented by ascertaining the conditions which here-

tofore interfered with the economically successful disintegration of metals into powders, it has become possible according to my invention to provide means for the carrying out of the process, and which are 70 particularly distinguished by great simplicity of construction, and in which wear of the operating parts of the mill is substantially avoided, so that the elements of the apparatus have a long life, while, on the 75 other hand, a great purity of the powder is obtained.

A preferred form of embodiment of the principles of my invention is shown by way of example upon the accompanying drawing 80 in a conventional manner, Fig. 1 being a vertical sectional view, and Fig. 2 being a view of the apparatus of a detail turned through ninety degrees.

In a casing 1 two shafts 2 and 3 are 85 mounted which are provided with air propellers or the like 4 and 5. In front of these air propellers the transverse members 6 and 7 are arranged, as more clearly shown in Fig. 2. The material to be comminuted, scrap, powder, granules or the like, is charged into the casing 1 through an opening 8 provided with a closure. Then the propellers 4 and 5 are given a rapid rotation in opposite direction by means of the 90 pulleys 9 and 10. The propellers 4 and 5 produce air currents which, as indicated by the arrows 11 and 12 impinge upon each other in the center part of the casing. The transverse members 6 and 7, moreover, produce lateral displacements of the air currents, so that the quantities of material carried by the air currents are not only caused to impinge upon each other, but will also be 95 frictionally engaged. The air propellers 4 and 5 draw the air from the lateral portions of the casing, forcing it against the center of the casing, and producing there a continuous violent impact of the air currents, the currents becoming distributed thereby 100 and being again projected towards the center, so as to set up a continuous circulation in which the several particles of material are compelled to participate. In order to cause the circulation to proceed in a satisfactory and sufficient manner it is advisable to provide in the casing 1 lateral cavities of sufficient extent at the rear of the air propellers, and of such size and shape as 105 to assist the formation of the air currents. The propeller blades 4 and 5 are of such pitch that the thrust of the air currents near the center is substantially equal to the thrust occurring at the outer extremities of the 110 blades.

The continuous thrust and impact of the individual metal particles upon each other produce, of course, considerable heating of the entire space of the mill and of the particles themselves. This heating of the par- 115 120 125

ticles is of advantage, inasmuch as the strength of most metals is considerably decreased with the rise of temperature, expediting the comminuting operation. The 5 heating of the mill itself requires a special formation of the journal bearing which will stand only a limited temperature, and this formation of bearing also becomes imperative from other reasons.

10 In constructing the apparatus referred to so as to conform with the requirements of practical operation it is of importance, in order to avoid abnormal dimensions of the shafts, to arrange the bearings as closely 15 as possible to the air propellers 4 and 5 in view of the very considerable forces generated in the casing and at the propellers. On the other hand, the provision of sufficient spaces for the required circulation at the 20 sides of the propellers being of advantage, would call for the construction of elongated bearings. Even, when securing the same against the penetration of particles of powder by suitable packing means, the bearings 25 are heated to such a degree that it becomes necessary to provide means to prevent excessive heating, water cooling being preferably employed. For this purpose the cavities 15 and 16 are provided through which 30 a circulation of cooling water may take place.

The currents generated in the apparatus are of such force that very considerable amounts of material, thus for instance pieces 35 of wire of from 2 to 3 millimeters in diameter and of about 6 to 7 millimeters in length are whirled around, without the air propellers 4 and 5 or the transverse members 6 and 7 becoming mechanically engaged with the great mass of grinding material deposited upon the bottom of the apparatus. The small pieces of wire, upon the beginning of the grinding operation, are first compressed at the ends by the force of 40 the impact so as to be given the configuration of small dumb-bells. Then, these compressed pieces are gradually pounded more and more, until after some time, almost the entire material in the mill has assumed an 45 almost globular shape. Even by the most careful tests no wearing out of the air propellers or of the transverse beaters could be ascertained after several hours operation. It is of some importance in connection with 50 the grinding procedure to maintain a certain proportion of the masses charged into the apparatus to the amount of air or of liquid contained in the apparatus. It is, of course, of advantage to charge as large as 55 possible an amount of material into the apparatus, while on the other hand, the formation of the air currents and the circulation of the material should not be interfered with. As a favorable proportion it has been 60 found that about two thirds of the space

should be filled with air or liquid, while the remaining one third should be filled with the material to be comminuted.

Through the admission conduits 17 and 18 air or other fluid or liquid may be introduced from the main conduit 19 into the mill so as to create a certain over-pressure therein, and thereby causing the finer particles to be discharged into the container 21 upon the opening of the slide 20 provided at the upper end of the mill. The space of the container 21 is provided with an air conduit 22 terminating in a tangentially shaped nozzle, the said air conduit 22 at the moment when the particles pass the nozzle, causing a considerable rarification of the quantity of air carrying the fine particles, and causing at the same time the bursting apart of any conglomerated or aggregated particles. These particles then ascend with 85 the increased air current within the container 21 which has a restricted portion at 90 23, and the upper extension of which constitutes a funnel 24. In consequence of the slowing up of the current in the interior of the upwardly enlarged funnel 24 the coarser particles are thrown down, and are caused to drop into the funnel 25 which is mounted below the restricted portion 23 within the container 21. The coarser particles may 95 then be returned from the funnel 25 into the casing 1. While this is done the air admission conduits 17 and 18 into the casing 1 are preferably closed. The various stages 100 of procedure, however, vary in accordance with the fineness of the powder it is desired to obtain. One may also operate continuously, or the slide 20 may be opened periodically. From the container 24 the air current is conducted to separating devices 26 in which it is submitted to filtration and the like by means of sifters, sieves 27 or similar means. The air current issuing from the short pipe 28 which is freed from admixtures of the powder may be used over again and returned to the apparatus through the conduit 22 or the tubes 17 and 18.

It is of importance in connection with the impinging of the several particles against each other, and for the production of the circulating movements, that the propellers 4 and 5 are not arranged in close proximity to each other, but, as experience has shown, preferably at a distance of from 10 to 20 centimeters from each other; but this feature as well as other considerations depend, of course, upon the particular kind of construction and the size of the mill, and the dimensions of its several parts are preferably determined in each case by experiments according to the kind of the material to be disintegrated. Obviously the invention also applies to the disintegration of materials other than metals. But at any rate, a certain distance between the propellers must 115 120 125 130

be observed for obtaining the highest possible degree of efficiency.

My invention is not restricted to the particular mode of operation and the particular arrangement of parts as above described by way of example and for illustrating purposes only, but modifications and changes may be made to suit different conditions, and without deviating from the principle of my invention.

I claim as my invention:

1. The process of converting hard materials to a finely powdered state, which consists in producing mutually impinging high-velocity whirling currents of gas or air in a closed space arranged to prevent said currents from passing each other, and causing said currents to circulate within said closed space in all directions at the rate of several thousand times, or more, per minute, thereby causing the particles of the material to continually impinge upon each other with great force.

2. The process as specified in claim 1, in which the velocity and pressure of the whirling currents are so increased that also heavy and tough metals, e. g. copper, tombac, lead, etc. are converted into a finely powdered state.

3. The process as specified in claim 1, in which to the whirling currents and the particles of the material carried thereby, such a movement is given as to cause them to impinge upon each other both in a rectilinear direction and a lateral direction.

4. In a device for pulverizing hard materials, the combination with an entirely enclosed casing filled with gas and air of means for producing therein mutually impinging whirling currents, and circulating them within said casing with great velocity, at a rate of several thousand times per minute, or more, and means for intermittently charging and discharging said casing.

5. In a device for pulverizing hard materials, the combination with an entirely en-

closed casing filled with gas or air, of propeller-shaped elements spaced from each other and from the walls of said casing, so as to provide open spaces around said members for producing a circulation of whirling currents all around said propeller-shaped members, means for revolving said members in opposite direction to each other with great velocity, at the rate of several thousand times, or more, per minute, and means for intermittently charging and discharging said casing.

6. In a device for pulverizing hard materials, the combination with an entirely closed casing filled with gas, or air, of propeller-shaped members spaced apart, so as to provide open spaces around said members in said casing for producing a circulation of whirling currents all around said members, transverse members disposed in front of said propeller-shaped members, means for revolving the opposed propeller-shaped members and transverse members in opposite directions relative to each other with great velocity at the rate of several thousand times, or more, per minute, and means for intermittently charging and discharging said casing.

7. In a device for pulverizing hard materials, the combination with an entirely enclosed casing, of means for admitting thereto a fluid, rotatable members for producing a circulation of whirling currents in said casing, means for revolving said members at a high rate of speed, means for intermittently charging and discharging said casing, a compressed fluid conduit connected to the discharging means, the latter having a funnel-shaped enlarged outer portion above said conduit, an open-ended funnel within said discharging means, and separating and fluid discharging means connected to said enlarged outer portion.

In testimony whereof I affix my signature.

EMIL PODSZUS.
